V. W. DUFF.

DEVICE FOR HOLDING ENGINEERS' TIME TABLES,
APPLICATION FILED FEB. 7, 1921.

1,423,920.

Patented July 25, 1922.

FIG. 1.

Inventor
V. W. Duff.
by Dring & Hague Attys

UNITED STATES PATENT OFFICE.

VERN W. DUFF, OF MOBERLY, MISSOURI.

DEVICE FOR HOLDING ENGINEERS' TIME TABLES.

1,423,920.

Specification of Letters Patent. Patented July 25, 1922.

Application filed February 7, 1921. Serial No. 448,170.

To all whom it may concern:

Be it known that I, VERN W. DUFF, a citizen of the United States, and a resident of Moberly, in the county of Randolph and State of Missouri, have invented a certain new and useful Device for Holding Engineers' Time Tables, of which the following is a specification.

This invention relates to improvement in devices for holding engineers' time sheets, and has for its object to provide means of simple, durable and inexpensive construction adapted to hold engineers' time sheets in such a manner and in such a position that the engineer or fireman may easily and accurately read the order written thereon without interfering with any operation which he may be performing.

A further object is to arrange the two outer sheets of a series of time sheets with their printed sides outermost, and to place and clamp them between two transparent members, such as sheets of glass, to hold the sheets straight and keep them clean, the transparent members being pivotally mounted in such a manner that each sheet may be turned to a predetermined position in such a manner that it may be easily read by either the fireman or engineer, and in this connection provide means for mounting a lamp in such a manner that the light may be on either of the sheets to be read when in either of its positions of movement.

Still a further object is to provide in such a device as above described, having transparent sheet supporting members, new and improved means for supporting and mounting said transparent members, and improved means for placing the sheets in operative positions between said transparent members.

These and other objects, which need not be mentioned in detail, will be apparent to those skilled in the art.

My invention consists in the construction, arrangement and combination of the various parts of the device, whereby the objects contemplated are attained, as hereinafter more fully set forth, pointed out in my claims and illustrated in the accompanying drawings, in which:

Figure 1 is a side elevation of my improved time sheet holding device.

Figure 2 is a central enlarged transverse sectional view of the same.

Figure 3 is a plan view of my improved device, showing the sheet supporting mem-

ber in dotted lines in one position of its movement, and also showing the lamp in several positions of its movement in dotted lines.

Figure 4 is a detailed sectional view of the means for locking the supporting frame in position, taken on the line 4-4 Figure 1.

Figure 5 is an enlarged detail sectional view of the locking mechanism for the upper side of the movable sheet supporting members.

My improved device comprises a bracket 10 having members 11 which are designed to receive screws for the purpose of securing said brackets to any convenient place in an engineer's cab. This is preferably, however, supported in such a manner that the device hereinafter described may be easily and quickly read by either the fireman or the engineer.

The member 10 is provided with two horizontally arranged parallel arms 12 being provided at their outer ends with pivot members 13 and 14, mounted in a rectangular frame 15. This frame 15 is provided with an inner frame member 16, having an inwardly extending flange 17 at one of its edges. This frame 16 is designed to receive a transparent plate 18, preferably formed of glass, which is held in place by any of the methods used in devices of this kind.

The frame 16 and plate 18 are of a size substantially equal to the dimensions of an engineer's time sheet, the frame 16 being of a width somewhat greater than the thickness of a series of time sheets such as is necessary for an engineer to complete a given run. The sheets are designed to be placed in the frame 16, with one of the sheets to be read adjacent to the glass 18, while another may be placed on the opposite side of the sheets and held in position by means of a glass plate 19. This plate 19 is mounted in a frame member 20 which is slightly smaller than the frame 16 so that it may be placed therein as shown in Figure 2. Each of the members of the frame 16 is provided with bracket members 21 near the lower ends. Each of said brackets is provided with an inwardly extending flange 22, the lower end of said flange being arranged to hold the lower end of the frame 20 in position within the frame 16. The said bracket 21 is formed triangular in shape so that the frame 20 may have the upper end swung outward to the position shown in dotted lines in Figure 2. The frame 20 will then limit the outward movement so that the instruction

sheets may be inserted between the plates 18 and 19. The top member of the frame 20 is provided with a strip 23 formed with an inclined face so that the sheets may be easily removed from the frame 20 by having their upper edges engage the said beveled face.

For securing the upper end of frame 20 in position within the frame 16, I have provided the latch 24 designed to co-act with 10 the pin 25 and the frame 16. The said pin 25 is designed to be received in a suitable opening in said member 24. This member 24 is provided with a curved portion with a straight end to enable the operator to easily 15 pull the frame 20 out of the frame 16.

By this construction it will be seen that I have provided means whereby a series of time sheets may be placed between two transparent plates and supported in an upright 20 position in such a manner that they may be easily read from either side. This provides means for supporting two sheets.

When the instructions from one of the sheets have been read and it is desired to 25 read the instructions on the other sheet, the frame 16 is swung upon pivots 13 and 14 through an angle of 180 degrees which places the opposite sheet in a position to be read.

The frame member 10 is provided with a 30 small bracket 26 having slidingly mounted therein a latch pin 27 upon which is mounted a spring 28. The outer end of the pin 27 is provided with a head 29, and its inner portion is provided with a washer 30 held 35 against movement on the pin 27 by means of a key 31, the washer being so placed that pressure from the end of the spring will cause the pin 27 to move inward. The other end of the said pin 27 is provided with a 40 central shoe 32 which is designed to engage the notch 33 formed in the outer face of each of the end members of the frame 16, thereby providing means for holding the frame 16 rigidly in position relative to the bracket 45 end.

The shoe 32 is so arranged that a slight pressure applied to the frame 16 will cause it to disengage the notch 33 when it is desired to swing the frame.

50 I have provided means for illuminating the sheets artificially, which comprises a bracket 34 mounted on the pin 14, which is considerably longer than the pin 13. The said pin 14 is provided with a collar 35 which is keyed thereto and is designed to carry the said bracket 34. For holding the bracket 34 in engagement with collar 35, I have provided a spring 36 which is mounted on the upper end of the pin 14, said upper 55 end of the pin being provided with a washer 37 designed to rest on the upper end of said spring, said washer being secured in position by means of a collar 38 secured to the pin 14 by means of a key 39.

65 The bracket 34 is bent upward and pro-

vided with a lamp socket 40 having a reflecting shade 41. The shade and lamp are set at such an angle that the rays of light from the lamp 42 will be thrown upon either of the plates 18 or 19, and then said bracket 70 member 34 is held substantially at the right angle to the frame 16. Figure 2 shows the lamp in position to throw the light on the plate 18. If it is desired to swing the frame 16 so that the plate 19 may be placed in a 75 readable position, the said frame 16 is swung in the direction indicated by the arrow in Figure 3. This will cause the member 42 on the bracket 34 to engage one of the pins 43 mounted on the upper face of the bracket 80 member 12 by the frictional engagement between the bracket 34 and the collar 35. The frame may then be swung to position with the plate 19 under the light.

If it is desired to swing the plate 18 so 85 it may be read from the opposite side of the bracket 10 from that shown in Figure 2, it will be desirable and necessary to move the light with the frame. This is accomplished by rotating the frame 16 in the 90 opposite direction from that shown by the arrow in Figure 3. This will cause the member 42 to disengage the pin 43 and the bracket 34 to follow the frame 16 by the frictional engagement of the collar 35 until 95 the opposite end of the member 42 is engaged by the opposite pin.

It will be seen that I have provided a device of comparatively simple, durable and inexpensive construction into which a series 100 of engineers' time sheets may be inserted in position to be read by either the engineer or the fireman. If the fireman desires to read the orders and they are in a position adjacent to the engineer, all he has to do is 105 simply rotate the frame 16 through an angle of 180 degrees. When he has finished, the frame may be then moved to its original position if so desired. The order sheets are always in a position where they can be read 110 even without the operators discontinuing the work which they may be performing.

By the arrangement of my improved lamp bracket the light may be carried with the sheets as moved from one position to another, or the sheets may be reversed under the light without any operation on the part of the operator any more than turning the frame 16 which requires less time than it would to turn a series of sheets.

115 New sheets may be easily inserted by moving the large member 24 slightly downward to disengage the pin 25, then permitting the upper edge of the frame 20 to be swung outward until the ends of the frame engage the 125 flange 22, after which the old sheets may be removed and new ones replaced.

I claim:

1. In a device of the class described, a bracket, a frame pivoted therein, one of said 130

5 pivots comprising a pin rigidly secured to said frame, a lamp bracket pivoted on said pin, means for frictionally engaging said bracket and said pin so that as the said frame is rotated, the said bracket will be rotated.

2. In a device of the class described, a bracket, a frame pivoted therein, one of said pivots comprising a pin rigidly secured to 10 said frame, a lamp bracket pivoted on said pin, means for frictionally engaging said bracket and said pin so that as the said frame is rotated, the said bracket will be rotated, and means for limiting the movement of 15 said bracket after it has moved through a predetermined angle.

3. In a device of the class described, a bracket, a frame, having parallel spaced transparent panels, pivotally mounted at its 20 central portion to swing in said bracket, said frame being provided with means whereby instruction sheets may be placed between said panels, a lamp adapted to be moved to position to throw light on either of said 25 panels, when in any of its positions of movement and also adapted to automatically follow the panels as they are moved through a predetermined angle relative to said bracket.

4. In a device of the class described, a bracket, means pivoted therein for supporting instruction sheets so that they may be moved to a position to be read from either side, one of said pivots of said means comprising a pin rigidly secured to said means,

a friction block secured to said pin, a lamp 35 bracket pivoted on said pin, adjacent to said block, yielding means for holding said bracket against said block, so that said bracket will be frictionally carried thereby and a lamp on said bracket for illuminating 40 the sheets of said panels.

5. In a device of the class described, a bracket, means pivoted therein for supporting time sheets, so that the said sheets may be moved to be read from either side, a 45 lamp adapted to be adjusted to throw light on either side of said sheets, and also adapted to automatically follow the said sheets as they are moved from one readable position to another.

6. In a device of the class described, a bracket, a frame pivotally mounted therein to swing in a horizontal plane, a transparent plate within said frame, a second frame pivotally mounted to the lower edge of said 55 first frame, said second frame being provided with a transparent member, and also designed to swing outward at its top to permit sheets of instructions to be placed between said transparent members, means for 60 limiting the outward movement of said second frame, and means for locking the upper edge of said second frame in position, with said transparent members substantially parallel to each other.

Des Moines, Iowa, January 18, 1921.

VEEN W. DUFF.
